CARBON PAPER PACK FOR MANIFOLDING
TYPEWRITERS

Joseph Carroll Doyle, Rochester, N. Y., assignor
to Kee Lox Manufacturing Company, Rochester, N. Y., a corporation of New York

Application February 16, 1951, Serial No. 211,353

1 Claim. (Cl. 282—1)

1

This invention relates to a carbon paper pack for use with a manifolding typewriter in which a series of sheets of carbon paper forming parts of different packs are each connected to a separate supporting bar or blade of a movable carbon paper carriage and interposed between continuous sheets of paper on which several typewritten records are to be made, the carbon paper carriage being withdrawn after each typing operation to remove the carbon sheets from between the record sheets and permit tearing off the typewritten records from the continuous record sheets, and it has for its purpose to afford a carbon paper pack which can be readily attached to the supporting bar of the carbon paper carriage and includes a multiplicity of folded sheets of carbon paper arranged so that the outermost sheet can be easily drawn from the pack and unfolded for use between two record sheets while the reserve folded carbon sheets are maintained in their superposed and folded relationship in the pack, and effectively protected so that the operator's fingers do not come in contact with the exposed carbon surface and the carbon sheets are protected against contact with the record sheets during movement of the carbon paper carriage.

A further purpose of the invention is to provide a construction in which a multiplicity of folded carbon paper sheets are attached at one end to a backing sheet, while they are protected and attached to the supporting bar of the carbon paper carriage by means of a wrapper which extends over the exposed carbon surface of the outermost carbon sheet and around the side edges of the folded carbon sheets, thence over the outer face of the backing sheet to which the wrapper is attached, leaving the folded carbon sheets free to be individually unfolded and drawn from the pack, while one end of the wrapper extends beyond the folded ends of the carbon sheets and is folded back upon itself to afford a flap that is engaged with the supporting bar of the carbon paper carriage, or is otherwise detachably associated with the supporting bar.

A further purpose of the invention is to afford a structure which is economical and simple to produce and in which the carbon sheets can be readily manipulated for use by the operator, and with a minimum waste of carbon paper.

To these and other ends, the invention consists in the construction and arrangement of parts that will appear clearly from the following description when read in conjunction with the accompanying drawings, the novel features being

2 pointed out in the claim following the specification.

In the drawings:

Fig. 1 is a plan view of a carbon paper pack 5 constructed in accordance with a preferred embodiment of the invention, and illustrating it in position on a supporting bar such as forms part of a carbon paper carriage of a manifolding typewriter;

10 Fig. 2 is a view in rear elevation of the carbon paper pack;

Fig. 3 is a view in elevation of the carbon pack, 15 showing the outermost carbon sheet partially withdrawn from the pack as when it is to be used between record sheets, the lower part of the partially removed carbon sheet being broken away;

Fig. 4 is a similar view showing the outermost carbon sheet entirely withdrawn from the pack 20 for use, its forward part being broken away and the next carbon sheet in position to be grasped and withdrawn;

Fig. 5 is a longitudinal central sectional view, 25 partially broken away, on line 5—5 of Fig. 1 looking in the direction indicated;

Fig. 6 is a transverse sectional view, partially broken away, taken on the line 6—6 of Fig. 1 and looking in the direction indicated, and

Fig. 7 is a plan view of the wrapper before 30 being folded around the carbon paper sheets and attached to the backing sheet.

Referring more particularly to the drawings in which like reference numerals refer to the same parts throughout the several views, the 35 structure shown, which indicates one way of carrying out the invention, comprises a series of carbon paper sheets 1 each folded outwardly upon itself with its carbon surface exposed. The several carbon paper sheets folded in this fashion have their rear ends alined and attached to a 40 paper backing sheet 2, see Fig. 5, which latter has a portion 3 folded around the alined rear ends of the carbon paper sheets and secured thereto by a line of stitching 4 which attaches the carbon paper sheets to the backing sheet 2. By referring to Fig. 5, it will be noted that the 45 forward end of each folded carbon sheet terminates a short distance from the line of stitching 4 so that the carbon sheets can each be readily grasped at its forward end and withdrawn from its position over the reserve supply of carbon sheets when it is to be placed in use.

In order to protect the exposed carbon-coated 50 face of the outermost carbon sheet from contact 55 with the fingers of the operator and to hold

the reserve supply of folded carbon sheets in proper relation to each other until each is withdrawn from the pack for use, there is provided a wrapper of paper or other suitable material that preferably surrounds the folded carbon sheets and backing sheet, extending around their side edges and being adhesively or otherwise attached to the backing sheet in any suitable fashion, the wrapper being constructed to enable its ready attachment to the supporting bar of the carbon paper carriage.

This objective is attained by a wrapper formed from a blank of paper, for instance such as shown in Fig. 7, and including a front portion 5 that overlies the outermost carbon sheet, see Figs. 1 and 7, rear portions 6 and 7 that extend around the side edges of the folded carbon sheets over the backing sheet 2, and an extension 8 that projects from one end of the central portion 5 and is folded to afford a flap 9 by which the wrapper is attached to the supporting bar 10 of the carbon paper carriage, while flap 9 protects the folded edges of the sheets of the carbon paper pack from contact with portions of the record sheets when the carbon paper carriage is withdrawn rearwardly of the record sheets.

The wrapper is preferably assembled by placing its front portion 5 in position overlying the exposed carbon surface of the outermost folded carbon sheet, then folding the rear portions 6 and 7 respectively around the edges of the carbon sheets and over the backing sheet 2, the rear portions 6 and 7 being preferably adhesively attached along their forward edges to the backing sheet 2 and portion 7 being adhesively attached to portion 6 along their overlapping edges, as indicated by dotted lines in Fig. 2, following which the end extension 8 is folded along a line that is spaced from the inner ends of the folded carbon sheets sufficiently to accommodate the supporting bar 10 of the carbon paper carriage.

When the extension is thus attached to the supporting bar 10 and removably secured thereto by metal clips 11, as customary in the use of such carbon paper packs, the flap 9 extends over the portions 6 and 7 and the backing sheet 2 preferably to approximately the position indicated in Fig. 2 and in dotted lines in Fig. 1. The wrapper is so dimensioned that when attached to the backing sheet 2, as shown in Fig. 1, the forward edge of the wrapper terminates a distance from the forward edge of the outermost carbon sheet, thus exposing a sufficient portion of the free edge of the carbon sheet to enable the operator readily to take hold of the sheet and withdraw it from the pack, while 12 designates a cutout portion centrally of the forward edge of the wrapper to afford ample space for the operator to grasp the sheet and to indicate the proper point for engaging the sheet when withdrawing the same.

It will be understood that while the wrapper surrounding the folded carbon sheets is adhesively attached to the backing sheet and fits tightly enough to prevent the carbon sheets remaining in the pack being accidentally dislodged, it fits with sufficient looseness around the car-

bon pack so that the operator can grasp the central portion of the forward edge of the outermost carbon sheet and withdraw it from the wrapper in the manner illustrated in Fig. 3 which shows the outermost carbon sheet partially withdrawn. When the carbon sheet is entirely withdrawn from the wrapper and is in position for engagement between two record sheets, it is related to the backing sheet and wrapper as illustrated in Fig. 4, and there is another carbon sheet immediately under the wrapper with the forward portion of its carbon face and its free edge exposed, ready to be withdrawn when the first mentioned sheet has been torn away from the backing sheet.

It will be understood that the carbon paper pack may be attached to the supporting bar in other ways than as described herein, and the essential feature of the invention resides in a wrapper surrounding the carbon sheets and attached to the backing sheet with provision for detachably securing the wrapper and carbon pack to the supporting bar.

While the invention has been described with reference to the particular construction herein shown, it is not restricted to the exact details disclosed and this application is intended to cover such modifications or departures as may come within the purposes of the improvement and the scope of the following claim.

I claim:

A carbon pack for manifolding typewriters comprising a multiplicity of superposed independently folded and outwardly folded sheets of carbon paper aligned at their ends and a backing sheet to which said carbon sheets are stitched at one end while the opposite end of each carbon sheet is free and has its carbon surface facing outwardly, a wrapper having a continuous and unbroken front portion extending across the outwardly facing carbon surface of the carbon sheet and rear portions extending around the side edges of the carbon sheets and across the outer surface of the backing sheet and secured to said outer surface of the backing sheet, the forward edge of said front portion of the wrapper terminating in spaced relation behind the forward edge of the outermost carbon sheet and exposing the latter to permit gripping and pulling out the exposed carbon sheet without disturbing the wrapper or the underlying carbon sheets, and an extension on the front portion of the wrapper projecting beyond the folded ends of the carbon sheets and having a folded portion which is detachably engageable with a supporting bar.

JOSEPH CARROLL DOYLE.
